UNITED STATES PATENT OFFICE

FRITZ LUTHER, OF DESSAU, GERMANY, ASSIGNOR TO G. POLYSIUS, OF DESSAU, GERMANY, A FIRM OF GERMANY

COOLING APPARATUS FOR ROTARY KILNS

Application filed May 26, 1927, Serial No. 194,511, and in Germany October 4, 1926.

This invention relates to rotary kilns and more particularly to the apparatus or parts employed therein to effect the cooling of the material after the burning or other heat treatment thereof.

In carrying out my invention, the cooling zone of the drum is provided with longitudinally extending sheet metal plates or baffles which project inwardly from the peripheral wall and serve to support an inner cylinder through which the burner extends. This results in the subdivision of the material into an annular series of separate streams or parts arranged around and spaced from the burner as distinguished from the usual single stream below the burner. Thus the quick cooling of the material is secured.

I have discovered that more effective results can be secured by making these plates or walls curved and of such thinness as to permit flexing under the weight of the material passing therebetween and which is supported in varying degree by the plates. Thus the inner edges are capable of moving radially as well as approximately tangentially of the inner cylinder, and the inner cylinder itself may move radially in respect to the outer cylinder. This construction has advantages from the standpoint of manufacture and also it effects a better cooling action. The relative movement of the parts during the rotation of the drum and the longitudinal feeding of the material facilitates the movement of the larger pieces of the clinker through the passages.

In the accompanying drawings, I have illustrated one embodiment of my invention.

In these drawings:

Fig. 1 is a central longitudinal section of one end portion of a rotary kiln;

Figs. 2 and 3 are transverse sections on the lines 2-2 and 3-3 respectively of Fig. 1; and Fig. 4 is a central longitudinal section through the whole kiln.

The invention may be applied to various types of rotary kilns, for instance, that shown in Fig. 4 in which the material enters the kiln at the right hand end and passes in the direction of the arrow through a preliminary heating zone 17, a calcining zone 18

to a clinkering zone 9. Beyond the clinkering zone is the cooling and discharge zone in which my improved construction may be incorporated. In this cooling zone there is mounted an inner cylinder 11 smaller than and spaced from the outer shell 16. This inner cylinder 11 is supported by a plurality of walls 12 which extend axially in approximately radial planes. Each of these walls or plates 12 is flexible and longitudinally curved, and they in connection with the cylinder 11 and shell 16, form an annular series of passages lengthwise of the drum outside of the cylinder 11.

As the drum rotates and the material in moving endwise reaches the end of the cylinder 11 and the walls 12, it is picked up by the successive walls 12 and carried around the axis of the drum, and thus is subdivided into separate portions which continue their flow lengthwise of the drum. As these separate streams are separately agitated during the bodily circumferential movement of the passages, the material in each stream has a greater exposed area and greater heat radiating surface. The passages also serve for the inflow of separate streams of air counter-current to the outflowing material. Thus due to the more effective contact with the air, the more effective agitation, and the more effective heat conduction, the material is effectively cooled before reaching the discharge ports 20.

Due to the flexibility of the walls 12, the cylinder may move to a limited extent in a radial direction so that the tumbling of the material in moving through the passages and around the cylinder 11 may cause a vibration of the cylinder which aids in the advancing of the material and the intermixing of the air therewith.

The clinkering zone may be provided with suitable heat insulating lining 14, and a portion of this of reduced thickness may extend part way along the shell 16 within the passages around the cylinder 11. The very hot material coming from the clinkering zone may be preliminarily cooled by the action of the blades 13 extending longitudinally and

serving as shovels or baffles to lift up and drop the material.

I have not illustrated any means for heating the drum as such forms no portion of my invention, but it will be understood that the usual burner pipe projects through the cylinder 11 toward or to the end of the enlarged clinkering zone.

This construction permits one to observe 10 the operation of the burner by looking through the cylinder along the burner tube, as none of the material flows out through the cylinder.

Having thus described my invention, what 15 I claim as new and desire to secure by Letters Patent is:

A rotary kiln having a cooling drum at the discharge end thereof, a hollow cylinder within said drum open at both ends and approximately concentric with said drum and spaced from the peripheral wall thereof, and longitudinally extending curved flexible plates supporting said cylinder from said drum, whereby the annular space between 25 the drum and the cylinder is subdivided into an annular series of separate passages for the outflow of the material, said plates being of sufficient flexibility to permit limited bodily movement of the cylinder radially of 30 the drum, whereby the cross-sectional form of said passages varies during the rotation of the drum.

Signed at Leipzig, in the state of Saxony, Germany, this fifth day of May, 1927,

35 A. D.

FRITZ LUTHER.
